Primary Examiner—Susan J. Lucas*Assistant Examiner*—Jennifer A. Regester*Attorney, Agent, or Firm*—Walker, McKenzie & Walker, P.C.[57] **CLAIM**

The ornamental design for a plaque support, as shown and described.

DESCRIPTION

FIG. 1 is a front elevational view of a plaque support, showing the preferred embodiment of the new design; FIG. 2 is a left side elevational view of the plaque support of FIG. 1, the right side being a mirror image thereof; FIG. 3 is a rear elevational view of the plaque support of FIG. 1;

FIG. 4 is a top plan view of the plaque support of FIG. 1; FIG. 5 is a bottom plan view of the plaque support of FIG. 1;

FIG. 6 is a sectional view of the plaque support of FIG. 1 as taken on line 6—6 of FIG. 1 on an enlarged scale to more clearly show certain ornamental features thereof.
